UNITED STATES PATENT OFFICE.

ALOIS TEGELE, OF NASHUA, IOWA.

RAILWAY-CROSSING GATE.

1,126,588.

Specification of Letters Patent.

Patented Jan. 26, 1915.

Application filed July 24, 1913. Serial No. 781,009.

To all whom it may concern:

Be it known that I, ALOIS TEGELE, a citizen of the United States, residing at Nashua, in the county of Chickasaw and State of Iowa, have invented certain new and useful 5 Improvements in Railway-Crossing Gates; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in automatically-operated gates for railways.

20 The invention comprises various details of construction and combinations and arrangements of parts which will be herein-after fully described, shown in the accompanying drawings and then specifically defined in the appended claims.

25 I illustrate my invention in the accompanying drawings, in which:—

Figure 1 is a top plan view of an apparatus embodying the features of my invention. Fig. 2 is a side elevation of the gate lowered into operative position. Fig. 3 is 30 an enlarged detail cross sectional view on line 3—3 of Fig. 1 through the rails of a railway and means for releasing the gate operating mechanism. Fig. 4 is a sectional view on line 4—4 of Fig. 1, parts being 35 shown in an elevated position, and Fig. 5 is a cross sectional view on line 5—5 of Fig. 1 through the rails of a railway and showing in elevation the post upon which the gate is mounted.

40 Reference now being had to the details of the drawings by letter, A, A designates the rails of a railway between which are the pivotal levers B, mounted upon the pins B', having their forward ends beveled as at B'.

45 A pin C is fastened to the inner edge of each lever B and guided by a strap C' fastened to the tie D. A coiled spring D' is interposed between said strap and the lever B and is positioned about said pin and serves 50 to normally hold a portion of the lever B in contact with the rail A. A depressible member E is pivotally mounted upon a pin E' secured to a rail A and its free end rests upon the upper face of the longitudinally 55 movable bar F, which latter has its inner end angled as at F' and engages the inner

edge of the lever B. A flat spring H, shown in Fig. 3 of the drawings, is fastened at H' at one end to a tie and its free end bears yieldingly against the under face of the bar 60 F. The bar F is provided with an elongated slot F² through which a stationary guide pin I passes, and J is an angle plate pivotally mounted upon a pivot pin K and to which plate the bar F is pivoted at K'. 65 The plate J is connected to a cable N which in turn is fastened to a spring N' secured to one end of a rod O which is held by the collar O' upon the side of the post or standard Q. Said cable N is fastened to a second 70 cable N² which passes about a pulley N³ and is secured to the lower end of a tilting lever L pivotally mounted upon the pin L' upon the post and which lever L has a shouldered portion L² adapted to normally engage a 75 notch L³ formed in the upper edge of the gate. A spring L⁴ is fastened at one end to the post or standard and its other end to the lower end of the lever L and serving to normally hold the lever L in a locked relation 80 with the gate L⁵, as shown in Fig. 4 of the drawings. Said gate L⁵ is pivotally mounted upon a pin L⁶ upon the standard and has depending therefrom a series of ropes L⁷. A spring L⁸ is fastened at one end to the 85 top of the standard and at its other end to a rod L⁹ which in turn is secured to the gate and serves as a means for partially supporting the gate when in the position shown in 90 Fig. 2 of the drawings.

An electrical terminal P is fastened to the gate adjacent to its pivotal point and connected by means of a wire P' with a battery P², while a contact member R is fastened to the top of the standard and has a wire 95 R' secured thereby which in turn has connection with a light R², having a grounding wire R³ fastened thereto, said terminal R being adapted to contact with the terminal P when the gate is closed, thus causing a 100 light to be turned on at night to signal that the gate is closed.

Adjacent to the standard upon which the gate is pivotally mounted and intermediate the tracks is a depressible bar T, having inclined ends T' and which have springs T² underneath the same, said bar T being positioned over the inner end of the tilting bar W which is pivotally mounted upon the rod X, the outer end of said bar W being pivotally connected at Y to the lower end of the vertically movable bar Y', which latter is 105 110

guided by the strap M upon the post or standard and which carries an anti-friction roller M' at its upper end, adapted to contact with the under edge of the gate L⁵ and serving to raise the gate to an elevated position as the bar T is depressed.

The operation of my gate will be readily understood and is as follows:—As the flange of a car wheel, moving toward the gate, 10 comes in contact with the free end of the lever B, the latter will be swung upon its pivot toward the opposite rail and, as the angled end of the bar F is in the path of the swinging lever B, a longitudinal 15 movement will be imparted to said bar and which, through its connections with the tilting bar L, will cause the same to disengage with the gate and allow the latter to swing down to the position shown in Fig. 2 of the 20 drawings. When the wheel comes in contact with the depressible member T, the gate will be thrown back to an upright or open position by means of the pivotal bars W and Y' and the latch bar L, which is spring- 25 pressed, will engage and hold the gate in its upright or open position. As the car wheel proceeds farther and comes in contact with the other depressible spring-pressed member E, after passing by the 30 gate, the member E will cause the adjacent bar F to be depressed, which will throw its angled end out of the path of the adjacent pivotal lever B and allow the latter to swing idly without releasing the gate. It 35 will be understood that the two oppositely disposed levers B and the mechanism for throwing the gate are of identical construction so that, when an engine approaching the gate from either direction comes in contact with a lever B, it will cause the gate 40 to be thrown down and, after passing the gate and coming in contact with the second lever, the latter will operate idly without allowing the gate, which has been previously 45 returned to its normal position by the engine, coming in contact with the plate T.

By the provision of a gate made in accordance with my invention, it will be noted that a simple and efficient automatic mechanism is afforded whereby the gate may be 50 automatically closed by a train approaching from one direction or the other and a signal also given, consisting of a light which is turned on by the closing of the circuit as the gate closes, the circuit being broken 55 when the gate is again opened.

What I claim to be new is:—

1. An automatic gate apparatus comprising, in combination with a standard, a gate 60 pivotally mounted thereon, a pivotal member for holding the gate in an elevated position, reversely arranged pivotal levers mounted between the tracks of a railway, springs normally holding said levers in contact with the inner faces of the rails of the 65

railway upon one side of the track, longitudinally movable, downwardly yielding bars, each having its inner end angled and in the path of one of said levers, connections between said bars and pivotal member, affording means whereby, as one of the bars is moved longitudinally by the swinging of a lever actuated by the wheel of a passing train, the pivotal lever may be operated, allowing the gate to close, reversely positioned depressible members bearing one upon each of said bars, one of said depressible members being adapted to be actuated after a longitudinal movement has been imparted to the angle ended bar as the train 70 approaches the gate, while the other depressible bar is designed to be depressed to release a similar angle ended bar out of the path of the other lever after the train has passed the gate, and means for returning the gate to its upright position, as set forth. 75

2. An automatic gate apparatus comprising, in combination with a standard, a gate pivotally mounted thereon, a pivotal member for holding the gate in an elevated position, reversely arranged pivotal levers mounted between the tracks of a railway, springs normally holding said levers in contact with the inner faces of the rails of the railway upon one side of the track, longitudinally movable, downwardly yielding bars, each having its inner end angled and in the path of one of said levers, springs bearing each against the under face of one of said bars, connections between said bars and pivotal member, affording means whereby, as one of the bars is moved longitudinally by the swinging of a lever actuated by the wheel of a passing train, the pivotal lever may be operated, allowing the gate to close, reversely arranged depressible members pivoted to the rails of a railway and each having a free end resting upon one of said longitudinally movable bars and adapted to be actuated by the wheel of a passing 90 train, one of said depressible members being adapted to be actuated after a longitudinal movement has been imparted to the angle ended bar as the train approaches the gate, while the other depressible bar is designed to be depressed to release a similar angle ended bar out of the path of the other lever after the train has passed the gate, and means for returning the gate to its upright 95 position, as set forth. 100

3. An automatic gate apparatus comprising, in combination with a standard, a gate pivotally mounted thereon, a pivotal member for holding the gate in an elevated position, reversely arranged pivotal levers mounted between the tracks of a railway, springs normally holding said levers in contact with the inner faces of the rails of the railway upon one side of the track, longitudinally movable, downwardly yielding bars, 115

each having its inner end angled and in the path of one of said levers, springs bearing each against the under face of one of said bars, connections between said bars and pivotal member, affording means whereby, as one of the bars is moved longitudinally by the swinging of a lever actuated by the wheel of a passing train, the pivotal lever may be operated, allowing the gate to close, 10 reversely arranged depressible members pivoted to the rails of a railway and each having a free end resting upon one of said longitudinally movable bars and adapted to be actuated by the wheel of a passing train, 15 one of said depressible members being adapted to be actuated after a longitudinal movement has been imparted to the angle

ended bar as the train approaches the gate, while the other depressible bar is designed to be depressed to release a similar angle 20 ended bar out of the path of the other lever after the train has passed the gate, a bar bearing against the under edge of the gate, and depressible means actuated by the wheel of a passing train for actuating said gate 25 engaging bar and serving to return the gate to an open position, as set forth.

In testimony whereof I hereunto affix my signature in presence of two witnesses.

ALOIS TEGELER.
